LADY'S CONVERTIBLE COAT

Henrik B. Jorgensen, 1228 Grant Ave.,
San Francisco, Calif. 94108

Filed Jan. 24, 1966, Ser. No. 724

Term of patent 14 years

(Cl. D2—184)

Fig. 1

Fig. 2

Fig. 3

Fig. 6

Fig. 5

Fig. 4

I claim:

The ornamental design for a lady's convertible coat, as shown and described.
